FELT PUNCHING MACHINE

Arthur L. Clements, Chicago, Ill., assignor to
 American Hair & Felt Company, Chicago, Ill.,
 a corporation of Delaware

Application November 12, 1949, Serial No. 126,773

7 Claims. (Cl. 28—4)

1

The invention relates to felt punching machines.

The main object of this invention is to improve the construction and operation of felt punching machines of the general type shown in the prior U. S. Patent No. 2,004,709, dated June 11, 1935, to Robert S. Phillips, and in this connection to provide lighter power beams, a more readily adjustable variable stroke drive for the power beams, shock absorbing springs on both working heads to level out the cycle of returning heads to working position to permit higher operating speeds, a stripper grid mounting for quick release and return to working position without regard to positioning to aid in quick removal of the needle board, an improved needle board clamping device for securely holding said board in place and permitting its quick release, a grid having tapered grid bars affording greater clearance below the tops of said bars to prevent clogging the spaces between the bars, particularly of advantage when punching damp or sticky material, means for removing dust and fibre from the lower part of the puncher to keep the machine clean while in operation, a pull out roll release, and a lower grid assembly by which the grids with different grid bar spacings may be used.

The invention further consists in the several features hereinafter set forth and more particularly defined by claims at the conclusion hereof.

In the drawings:

Fig. 1 is a front elevation view of a machine embodying the invention, parts being broken away and parts being shown in section;

Fig. 2 is a detailed vertical sectional view taken on the line 2—2 of Fig. 1;

Fig. 3 is an end elevation view of the machine;

Fig. 4 is a vertical sectional view through the machine taken on the line 4—4 of Fig. 1;

Fig. 5 is a horizontal sectional view through the machine taken on the line 5—5 of Fig. 1;

Fig. 6 is an enlarged elevation view of one end of the machine, parts being broken away and parts being shown in section;

Fig. 7 is a detailed perspective view of the needle board and the stripper grids;

Fig. 8 is a detailed plan view of a portion of the upper grid, parts being broken away and parts being shown in section;

Fig. 9 is a detailed plan view of a portion of the lower grid, parts being broken away;

Fig. 10 is a detailed vertical sectional view of the needle board and grids in the punching position thereof, parts being broken away;

2

Fig. 11 is a detailed view of an end portion of one of the lower grid bars.

Referring to Figs. 1 and 2, a supporting frame is formed by spaced sets of end standards 12 which are rigidly connected together at their top portions by the angle members 13, at their medial portions by the channel members 14, and at their lower ends by the channel members 15. Each standard 12 includes spaced uprights 16 connected together by transverse frame members 17, and the outer standard also includes an upright 18.

An upper power beam 19, and a lower power beam 20 are mounted in the frame to reciprocate toward and away from each other.

Referring to Figs. 1, 3, and 4, the beam 19 includes longitudinally extending side plate 19a, a bottom plate 19b, end plates 19c, and spaced transversely disposed members 19d. Sets of 20 pairs of spring guide rods 21 are mounted at their lower ends on the members 19d, the rods 21 of each pair being pivotally connected at 22 to one of the members 19d and extending upwardly through openings 23 in transverse frame members 24. A spring 25 is disposed over each rod 21 between the member 24 and a plate 25a common to the sets of pairs of these rods 21, nuts 26 on the threaded ends of these rods holding the plate in operative position. The springs 25 act as shock absorbers to level out the cycle of returning said beam and permitting higher operating speeds. They also counterbalance the weight of the reciprocating parts.

The lower power beam 20 includes longitudinal 35 extending side plates 20a, end plates 20b, and a bolster or base board member forming a lower grid structure 20c. This beam at spaced points carries bracket 20d in which pairs of spring guide rods 27 are slidably mounted. The rods 40 27 are mounted at their lower ends on plates 28 carried by the frame members 15. Springs 29 mounted over the rods 27 are interposed between the brackets 20d and the plates 28 and similar to the springs 25 act as shock absorbers 45 for the lower beam to permit higher operating speeds and act to counterbalance the weight of the reciprocating parts.

A drive motor 30 is mounted on the top of a variable speed transmission 31 whose input shaft 50 is connected to the motor by a belt and pulley drive 32 and whose output shaft is connected by a belt and pulley drive 33 to the machine drive shaft 34. The base of the transmission 31 is 55 adjustably clamped by bolts 35 to channel frame members 36.

As shown in Figs. 1 and 3, the shaft 34 is mounted in end bearings 37 and intermediate bearings 38. The end bearings 37 are mounted for lengthwise adjustment on the transverse frame members 17 by the clamping plates 37a and bolts 37b. The bearings 38 are mounted for lengthwise adjustment on the transverse frame members 39 by the clamping plates 38a and bolts 38b. The shaft 34 has balancing wheels 40 mounted thereon at each end and oppositely disposed eccentric cranks 41 adjacent each end.

The upper beam 19 is connected at each end for movement relative to the frame by parallel links or levers 42, one of the ends of each link being pivotally connected at 43 to an end plate 19c of said beam and the other end of said link being pivotally connected at 44 to the frame. The lower beam 20 is similarly connected by parallel links or levers 45 to the frame for movement relative thereto. An eccentric strap or connecting rod 46 is mounted on each eccentric 41, and its lower end 47 is pivotally connected at 48 to a block 49 which is lengthwise adjustably mounted on the upper end of each of the links 42 or 45 and is clamped thereto in adjusted position by bolts 50. Thus the drive through eccentrics 41 and their connections with the beams 19 and 20 acts to move said beams toward and away from each other, and the extent of their movement or stroke is controlled by the positioning of the blocks 49 at varying distances from the centers of oscillation of the links 42 or 45, the lengthwise adjustment of the shaft 34 and the transmission 31 being made to accommodate the adjustment of said blocks 49.

A needle board 51 provided with punching needles 52 is mounted against the lower face of the bottom plate 19b. In machines of this kind, needle breakage occurs sooner or later, so that in order to keep the machine operating, replacement boards must be available and the replacement accomplished as quickly as possible. Means are accordingly provided for releasably clamping the needle board 51 to the beam 19, see Figs. 1, 2, and 4, comprising a series of spring engaged clamps for opposite sides of the board, and means for quickly releasing these clamps. Each clamp comprises an angled clamping plate or jaw 53 carried on the beam 19 and slidably guided by bolts 54 working in vertical slots 55 in said plate. Each plate 53 has a vertically disposed tappet or headed plunger 56 anchored thereto by nuts 57 and slidably extending through an angle iron guide bracket 58 secured to the beam. A spring 59 is interposed between the bracket 58 and the head of the plunger 56, so that each clamp is held in spring tensioned engagement with the outer edge of the bottom of the board 51. For quickly releasing all the clamps, spaced cam shafts 60 are journaled in spaced bearings 61 mounted on the beam, and each shaft has a series of cams 62, one for each plunger 56 whereby turning said shafts 60 will cause the cams 62 to move the tappets or plungers 56 and consequently the plates 53 downwardly against the pressure of the springs 59 to permit withdrawal of the damaged board and replacement with a new one. For simultaneously operating the shafts 60, each shaft is provided with a centrally disposed worm wheel 63 meshing with a worm 64 on a shaft 65 journaled on the beam 19 and extending transversely thereof and provided with a removable operating hand crank 66, whereby turning said shaft 65 by the crank 66 will rotate the shafts 60 in the

desired direction to either release the spring pressure or permit it to hold the clamps 53 in operative position.

The felt bat to be punch felted is introduced between the bolster or grid 20c and a fixed upper grid 67. As shown in Figs. 7, 8, and 10, the grid 67 comprises a marginal frame 67a and a series of round grid rods 67b. Each rod 67b at its ends is anchored to the frame 67a by its mounting in a bore 68 of the head of a bolt 69 clamped to the frame 67a by a nut 70. The grid frame 67a carries a series of spaced brackets 71 on opposite sides thereof, each of which carries an upright rod 72. Each rod 72 has its upper end working in a cylinder 73 fixed to the frame of the machine and carries an arm 74 connected to a shaft 75 by a toggle linkage comprising spaced crank arms 76 mounted on the shaft 75 at its side of the machine and pivotally connected by a pin 77 to one end of a link 78 whose other end is connected by a pin 79 to the arm 74. Each shaft 75 is oscillated by a crank handle 80 secured thereto. When the shaft 75 at the right in Fig. 4 is turned counterclockwise and the shaft 75 at the left turned clockwise to throw the toggle linkages over dead center, as shown in Fig. 4, the stripper grid 67 is held in its operative relatively fixed position with the arms 74 abutting rubber collars 81 interposed between them and the cylinders 73. When the right hand shaft 75 is turned clockwise and the left hand shaft turned counterclockwise, the toggles are broken and the rods 72 are moved downwardly by the linkage above described to move the grid 67 downwardly to a position in which it is clear of the needles 52 on the board 51 to permit replacement.

The punched felt is removed from the machine by a pair of longitudinally extending pull-out rollers 82, extending lengthwise of the machine and one of whose end mountings is shown. The lower roller is journaled at its end in bearings 83 mounted on the frame of the machine. The upper roller 82 is mounted at its ends in journals 84 which are slidably supported on fixed rods 85, carrying springs 86 acting to move said journals downwardly to bring the rollers 82 into operative feeding relation with the punched felt F.

The lower roller is driven from one end by a sprocket 87 on the shaft for said roller connected by a chain 88 with a sprocket 89 mounted on a shaft 90 mounted on the frame and which may be driven in any suitable manner as by a chain and sprocket drive connection 91 with the shaft 34, as shown in Figs. 1 and 3. For quickly releasing the pull-out rolls 82 from driving relation, a toggle linkage including links 82a and 82b operatively connected together and to the shaft for said rollers is provided, one of the links 82b provided with a handle 82c.

For removing dust and fibre that results from the punching operation, an endless spaced flight conveyor 92 is mounted at the base portion of the machine beneath the power beams and runs over rollers 93, one of which is driven by a chain and sprocket drive connection 94 with a speed reducer 95 associated with a drive motor 96.

For punching various types of stock, the spacing of the grid bars 97 of the lower grid structure 20c and their width have to be varied. To permit of ready changing of this spacing and the bars, each grid bar 97 has a notch 98 at each end extending down from its top and a two part marginal frame comprising a plane base frame part 99 and a notched top frame part 100 secured

together by machine screws 101 is provided. The notches 102 are milled in the part 100 at the desired angle, and this part is undercut, as shown in Fig. 10, to provide a recess 102a to receive the extension 104 of the notched end of the bar 97 which is clamped in operative position when the two parts 99 and 100 are clamped together by the screws 101. It is also to be noted that each grid bar 97 tapers downwardly on both sides so that its bottom edge is of less thickness than its top edge, thus forming a space 103 between the grid bars of gradually increasing size toward the bottom of the grid which greatly aids in preventing clogging of the spaces between the bars during the operation of the machine.

The general operation of the machine is similar to that shown in the prior Phillips Patent No. 2,094,709, one or more fibrous bats, either with or without reinforcement is conveyed by a conveyor, such as shown in Fig. 3 of said patent, between the lower and upper grids. While the bat or bats is or are slowly fed through the machine, the shaft 34 is rotated causing the oscillatory movement of the beams 19 and 20 and consequently the needle board 51 and the grid 20c, respectively connected to said beams as previously described. During this movement the grid 20c moves upwardly toward the stripper grid 67 compressing the bat between these parts, and as said grid 20c moves upwardly, the needle board 51 moves downwardly forcing the barbed needles into and through the bat, so that the fibres thereof are efficiently interlocked with each other and then, as the grid 20c moves downwardly, the needle board 51 moves upwardly and the needles 52 are, with the aid of the upper stripper grid 67 which holds the stock against upward movement, withdrawn from stock. This cycle is repeated with great rapidity, and it is to be noted that unlike the prior patented structure as the beams 19 and 20 are moved toward each other, the springs 25 and 29 act to absorb shocks.

The conveyor 92 discharges the waste into a pit or discharge chute below the drive end of said conveyor and indicated at 104.

I desire it to be understood that this invention is not to be limited to any particular arrangement or construction of parts except in so far as such limitations are included in the appended claims.

What I claim as my invention is:

1. In a felt punching machine, the combination of a frame, a needle board carrying power beam, a bolster carrying power beam, oscillatory levers respectively connecting the ends of each power beam to said frame, a drive shaft mounted on said frame and having oppositely disposed eccentric cranks at the ends thereof, connecting rods operatively connecting said cranks to the intermediate portions of said levers, means for adjusting the points of connections of said connecting rods lengthwise of said levers, and means for adjusting said drive shaft relative to said frame in accordance with the adjustment of said rods on said levers to vary the stroke of said power beams relative to each other.

2. A felt punching machine as defined in claim 1 wherein a pair of oscillatory levers is respectively connected to each end of each power beam and to said frame and the connecting rods are connected to one of each pair of said levers.

3. In a felt punching machine, the combination of a reciprocating power beam, a needle board, and means for detachably securing said needle board to said frame comprising a series of clamps engageable with said board, spring means for holding said clamps in clamping position, and rotatable means mounted on said beam and engageable with said clamps for simultaneously relieving said clamps of holding pressure of said springs.

4. In a felt punching machine, the combination of a reciprocating power beam, a needle board, means for detachably securing said needle board to said frame comprising a series of clamps 15 at each side of said board for holding the board against said beam, spring operated means for moving said clamps to clamping position, cam means for moving said spring operated means to a clamp release position, and means for simultaneously operating all of said cam means.

5. In a felt punching machine, a grid structure comprising a two part marginal frame and grid bars, one of said parts being notched to hold said grid bars in spaced relation and also being recessed below said notches, the ends of said grid bars being notched to engage in said recessed portion of said parts, and means for clamping the parts of said frame together with the notched portions of said bars between them.

30 6. In a felt punching machine, the combination of a needle board carrying power beam, a bolster carrying power beam, a relatively fixed grid cooperating with said needle board and bolster, means for moving said power beams toward and away from each other, a pair of pull-out rollers for the punched stock, means for driving one of said rollers, a movable support for the other of said rollers spring means acting on said support for yieldingly urging said other roller into feeding relation with said driven roller, and toggle linkage means connected with said movable support for quickly moving said yieldingly mounted roller out of feeding relation with said driven roller and against the pressure of said spring means.

7. In a felt punching machine, the combination of a frame, a reciprocating power beam, a needle board detachably mounted on said beam, a stripper grid beneath said needle board and cooperating therewith, and means for mounting said grid on said frame for movement to an operative position relative to said needle board and to a position clear of the needles on said board to permit removal of said board comprising a series of vertically movable members connected to each side of said grid, and a toggle linkage connection between these members and said frame.

80 ARTHUR L. CLEMENTS.
